UNITED STATES PATENT OFFICE.

HENRY W. SATTLER, OF MERIDEN, CONNECTICUT, ASSIGNOR TO THE HOBSON & MOTZER CO., OF MERIDEN, CONNECTICUT, A FIRM COMPOSED OF HARRY C. HOBSON AND ALFRED MOTZER.

COVER-SUPPORT.

1,300,027.

Specification of Letters Patent.

Patented Apr. 8, 1919.

Application filed January 9, 1919. Serial No. 270,397.

To all whom it may concern:

Be it known that I, HENRY W. SATTLER, a citizen of the United States, residing at Meriden, in the county of New Haven and 5 State of Connecticut, have invented a new and useful Improvement in Cover-Supports; and I do hereby declare the following, when taken in connection with the accompanying drawings and the characters of reference 10 marked thereon, to be a full, clear, and exact description of the same, and which said drawings constitute part of this application, and represent, in—

Figure 1 a broken perspective view illustrating a case and cover, the cover being supported in the open position.

Fig. 2 a broken inside view of the case and cover with the cover in the closed position.

Fig. 3 a broken side view of my cover support shown in the position ready for final closing.

Fig. 4 a top or plan view of the supporting flange.

This invention relates to an improvement 25 in cover supports particularly adapted for use in connection with cabinets, such as phonograph cabinets or covered boxes for various purposes. It is frequently desirable to support the cover in the open position 30 and it is also desirable to close the cover with one hand without releasing some locking mechanism with the other hand.

The object of this invention is to provide simple means whereby this may be accomplished, and the invention consists in a 35 cover support having certain details of construction as will be hereinafter described and particularly recited in the claims.

In carrying out my invention, I employ a 40 plate 5 formed with a flange 6, this plate being adapted to be secured to the inner side wall 7 of a box or cabinet. In the flange is a longitudinal slot 8 narrower at its inner end which is crossed by a bar 9. At the 45 outer end of the slot is a notch 10 for the purpose as will hereinafter appear. Pivotally connected with the cover 11 through a plate 12 is a brace 13 which is adapted to travel in the slot 8 and enter the contracted 50 inner end 9 thereof, being formed in its rear edge with a notch 14 forming a hook which will engage with the bar 9 so as to support the cover in the open position. Parallel with the forward edge is a slit 15 which extends

outward through the forward edge of the 55 brace 13 so as to form a spring arm 16 the lower end 17 of which is curved outward to form a finger for the purpose as will herein-after appear. In the closed position the parts are as shown in Fig. 2 of the drawings, 60 the brace being so positioned that when the cover is in the closed position it hangs vertically through the slot 8 in the flange 6.

As the cover is raised the brace rides against the bar 9 until the notch 14 engages 65 with that bar and so supports the cover as shown in Fig. 1 of the drawings. To close the cover, the cover is moved backward slightly so as to draw the brace upward through the slot, the spring finger 16 yielding to permit such movement, and the brace is prevented from being drawn entirely 70 through the slot by means of a stop pin 18. When the brace is drawn outward to the limit of its movement, the arm 16 springs 75 outward so that the finger 17 bears upon the upper surface of the flange 6. If the cover is then closed, the finger 17 will ride upon the upper surface of the flange 6 until that finger reaches the notch 10 through which it 80 will pass so that the cover can be completely closed. I thus accomplish with very simple mechanism the desired result of being able to firmly support a cover in open position and able to close that cover with one hand. 85

I claim:—

1. A cover support comprising a horizontally arranged flange, a longitudinal slot in said flange contracted at its rear end and formed with a transverse bar, a notch opening into the forward end of said slot, a brace extending through said slot and formed in its rear edge with a notch adapted to engage with said bar, said brace also formed with a spring arm terminating in an outwardly 90 projecting finger adapted to ride upon the upper surface of said flange and pass through the notch therein.

2. The combination with a casing, of a plate secured thereto, said plate formed with an inwardly projecting horizontally arranged flange, said flange formed in its upper face with a longitudinal slot contracted at its inner end, a bar crossing the inner 100 end of the slot, a notch opening into the forward end of the slot, a cover, a brace pivotally connected with said cover and extending downward through said slot, said

brace formed in its rear edge with a notch adapted to engage with said bar, said brace slotted to form a spring arm which terminates in an outwardly projecting finger, and 5 a stop to limit the upward movement of said brace.

In testimony whereof, I have signed this

specification in the presence of two subscribing witnesses.

HENRY W. SATTLER.
